FIG. 6

FIG. 7

FIG. 8

FIG. 9

FIG. 10

FIG. 11

FIG. 12

FIGURE 1 is a perspective view of a slipper showing a first embodiment of my new design as it appears in wearing position;

FIGURE 2 is a top plan view of said first embodiment as it appears in non-wearing position;

FIGURE 10 is a top plan view of said third embodiment as it appears in non-wearing position;

This application is a continuation-in-part of my earlier applications, Serial Number D. 71,020, filed July 23, 1962 (now abandoned), Serial Number D. 73,997, filed March 13, 1963, and is a continuation of my earlier application Serial Number D. 76,642, filed September 19, 1963 (now abandoned).

I claim:

The ornamental design for a slipper, substantially as shown and described.
